WASTE FITTING FOR BATHS AND THE LIKE

Felix Klein, Brunn, Mahren, Czechoslovakia

Application February 23, 1937, Serial No. 127,140
In Czechoslovakia February 21, 1936

3 Claims. (Cl. 4—203)

(Granted under the provisions of sec. 14, act of
March 2, 1927; 357 O. G. 5)

This invention relates to a waste fitting for baths, lavatory basins, sinks and the like, of the kind comprising a valve operating element in the form of a flexible wire or cable which is guided in a sheath and connected at one end to an operating handle while the other end is arranged so as to abut against the waste valve for opening the latter.

The object of the invention is to obtain a device of this kind which will operate durably in an efficient manner, and the invention consists essentially in providing the waste valve with a hollow stem fitted with guide wings and adapted to accommodate the ends of the wire and of its guide sheath, so that the wire will be positively guided and maintained in a central position relative to the valve and ensure free movement of the latter and so that the end of the sheath will be protected from the water by the enclosed air.

20 Further improvement in the wire guide is obtained by enclosing the sheath in a pipe which is supported in the valve casing and which projects together with the sheath into the valve stem.

Fig. 1 of the accompanying drawing represents 25 a sectional view of the operating element of a waste fitting constructed according to the invention.

Fig. 2 is a sectional view of the actual waste fitting.

30 Fig. 3 is a sectional detail view on an enlarged scale.

Fig. 4 is a sectional view of a valve operating element of modified construction.

Fig. 5 is a sectional view of a modified waste 35 fitting, and

Fig. 6 is a sectional view showing a further modification of the fitting.

Referring first to Fig. 2 it will be seen that the waste fitting comprises a flanged, cylindrical valve casing 3 which is clamped by means of a nut 18 to the bottom of the respective bath, sink, or other vessel, and which is fitted with a waste valve 1. The latter is provided with a bell-shaped stem 4 and with wings 2 which guide the valve and maintain it in its proper position within the casing. For operating the valve, a flexible steel wire or cable 7 is provided which abuts at one end against the valve inside the stem 4 and which is preferably provided with a thrust member in the form of a ball 11. The wire 7 is guided in a sheath 8 composed of a coil wire or band which may in its turn be enclosed in a protecting jacket 5. The sheath is closed at the ends by means of caps 10 provided with apertures through which the wire 7 projects. The sheath enters the valve stem 4 to-

gether with the wire 7 and is held in position by a bridge piece 6 whereby it is secured to the valve casing. The valve casing has a lateral inlet through which the wire and sheath are admitted, and the sheath is tightened to the casing by means of a gland 17 and a packing. The gland enters an internal enlargement in the casing which enables the outside of the latter to remain smooth for the reception of the nut 18.

The operation of the valve is effected through 10 the medium of a knob or handle which is connected to the wire 7 which can be arranged in any convenient position and at any suitable distance from the valve. The handle 13 shown in Fig. 1 is secured to a plunger 12 which is guided 15 in a sleeve 14 connected to any suitable adjacent support. A second sleeve 15, screwed on to the sleeve 14, holds the end of the sheath 8 which is secured in position by means of a set screw 16.

Fig. 4 shows a modification of the operating 20 device which in this case comprises a double-armed lever 23 fitted with a handgrip 22. The lever is pivoted to brackets mounted on a supporting base 26 to which the sheath 8 is secured by means of a nut 27. The wire 7 is connected 25 to a pivot 24 at one end of the lever, so that the valve will be operated when the lever is rocked. The elements, with the exception of the handgrip 22, are enclosed in a casing 25.

In the modified arrangement shown in Fig. 5, 30 the valve casing 3 is fitted with a pipe 19 which is secured to the bridge piece 6 and which opens at one end through the side of the casing, the opposite end of the pipe being located within the bell-shaped stem 4 of the valve 1. A cap 20, which 35 closes the end of the pipe, is screwed into the pipe and at the same time on to the sheath 8 so as to secure the latter in position. In this case there is no need for any packing gland, and the outer protecting jacket for the sheath may be 40 omitted.

In the further modification shown in Fig. 6 a pipe 19', mounted in the same way as the pipe 19 just described, is led through a T-piece 28 which connects the waste pipe to the overflow. 45 In this case the sheath 8 may be carried through the overflow pipe to the operating handle.

The device may be modified within the scope 50 of the invention as defined by the appended claims.

I claim:

1. A waste fitting for baths and the like comprising a casing, a waste valve in said casing having a hollow stem and guide wings on said stem, an operating handle, a flexible wire connected at 55

one end to said handle and abutting at the other end against said valve within its hollow stem by means of a ball thrust member, a guide sheath for said wire in the form of a flexible coil fitting snugly around the whole length of said wire except for the operating ends thereof and having one end located within the stem of the valve, caps for closing the ends of said sheath, means for supporting said sheath within the casing and means for supporting said operating handle.

2. A waste fitting for baths and the like comprising a casing, a waste valve in said casing having a hollow stem and guide wings on said stem, an operating handle, a flexible wire connected at one end to said handle and abutting at the other end against said valve within its hollow stem, a guide sheath for said wire having one end located within the stem of the valve, a pipe supporting

the sheath within the casing and projecting together with the sheath into the valve stem, a closing cap removably mounted on the end of said pipe and on to the end of the sheath, and means for supporting said operating handle. 5

3. A waste fitting for baths and the like, comprising a casing, a waste valve in said casing having a hollow stem, an operating handle, a flexible wire connected at one end to said handle and abutting at the other end against said valve within its hollow stem, a guide sheath for the entire length of said wire except for its operating ends and having one end located within the stem of the valve, means for supporting said sheath within the casing and means for supporting said operating handle. 10 15

FELIX KLEIN.
